(57) **CLAIM**

The ornamental design for a novelty screw on bottle cap having lips, as shown and described.

DESCRIPTION

FIG. 1 is a perspective view of a novelty screw on bottle cap having lips, showing my new design;
FIG. 2 is a front view thereof;
FIG. 3 is a back view thereof;
FIG. 4 is a right side view thereof;
FIG. 5 is a left side view thereof;
FIG. 6 is a plan top view thereof;
FIG. 7 is a plan bottom view thereof; and,
FIG. 8 is a another perspective view thereof.
The broken line showing depicted in the figures form no part of the claimed design.
